PULL TOY

Albert Behrens, New York, N. Y.

Application April 3, 1945, Serial No. 586,406

4 Claims. (Cl. 46—104)

1

This invention relates to toys of the kind usually referred to as pull toys—meaning a toy that when either pulled, or pushed, has some part or member of the toy either rotate or rock, as a result of progression of the toy along a flat surface such as a floor.

Whereas, toys of this type have heretofore been of wood, there is a current tendency to make them of some molded plastic material and, in so doing, the plastic manufacturer prefers to deliver to the toy-maker the body of the toy completely formed. That is, even though the body of the toy is initially formed from two sectional parts, the parts are secured together when delivered to the toy maker. The body usually has a cavity in its body portion and other openings are provided through which the toy maker may insert or assemble any moving parts plus further decorative features such as the head or tail, or both; for instance, if the toy is to simulate an animal like a dog, bear, elephant, and so on.

This invention relates to such a toy and especially one that has a head or tail, or both, that are to be rocked when the toy is moved along a floor. The object of the invention is to devise the parts thereof and their assembly so that they may be inserted readily in the unfinished toy body as delivered to the toy maker by the plastic manufacturer. The invention, therefore directs itself toward an arrangement of parts which can be inserted into the plastic toy body through openings or cavities left in the body by the plastic manufacturer. Other objects and features of advantage will appear as this specification proceeds.

The invention has been illustrated in the accompanying drawings by showing therein the best embodiment of the invention now known to me, but this is shown for illustrative purposes and not as limitations for, obviously, the invention is capable of other embodiments with other arrangements of details of construction, so the metes and bounds of the invention are defined in the appended claims.

In the drawings, Fig. 1 shows an elevational side view with parts broken away. Fig. 2 shows a bottom view. Fig. 3 is a partial perspective view, with parts broken away. Fig. 4 shows a sectional detailed view. Fig. 5 is a view showing the manner of the assembly of parts. Fig. 6 is a perspective view of the clamp.

In the drawings, there is shown a main body portion generally indicated at 11, made up of two complementary body sections 12 and 13 secured together to form the body portion which is minus a head 14 and tail 15, but provided with a ver-

2

tically slotted or winged head aperture or bore 16, and a tail aperture or bore 17, the bores 16 and 17 being in horizontal alignment with each other. Also the body is provided with a cavity 18 extending upwardly into the body of the toy from the bottom thereof and disposed equally into each body section 12 and 13.

On the side or side-wall of each cavity 18 is provided a pair of vertically disposed parallel blocks or ribs 20 and 21 leaving space 22 therebetween, and just below these blocks and substantially aligned therewith is a larger and longer block 23 extending upwardly from the lower edge of the cavity 18 having a partial groove 24 extending longitudinally thereof from the bottom of the block adjacent to but not complete to the top of the block. Extending laterally from the top region of this groove 24 is a recess 25.

30 represents a rockable shaft having a cross-arm 31 located about midway of its length. This shaft is designed to extend longitudinally through the toy body 11 and held in place in apertures 16 and 17, but having its ends 32 and 33 projecting from the toy body to have secured thereto the head 14 and tail 15, respectively.

In the cavity 18 is located a friction wheel 40 reaching outside of the cavity to engage the floor over which the toy is pulled. The wheel is journaled on or rotatable upon a fixed metal axle, having a straight section 42 and two wing sections 43 extending at an angle to the straight section 42. On each side of the wheel 40 is secured a cam 44, having diametrically opposed edges 45 and 46. 47 represents a sliding block or pusher member or tumbler disposed in the space 22 between fixed blocks 20 and 21, but long enough to remain in that space while reciprocating therein due to engagement with its lower end by the cam edges 45 and 46, meanwhile engaging one arm 48 of the cross-arm 31 on the rockable shaft 30.

The parts 20, 21, 22, 23, 24, 25, 43, 44, 45, 46 and 47 are duplicated in connection with each complementary body section 12 and 13, respectively. 50 indicates a spring metal loading clamp having each leg longitudinally slotted at 51 from their free end 52, partially of their length.

Operation.—The rockable shaft 30 is first threaded into the head aperture 16 by turning the cross-arms 31 vertically to enter that vertically slotted aperture or bore. Thereafter the shaft is turned 90° so that the cross-arms extend horizontally and the shaft is threaded into and through the tail aperture or bore 17. Next, various parts are assembled to be clamped together 55 by the loading clamp 50 in the relationship in

which they operate; that is, the friction wheel 40 and the cams 44 that it carries, the axle 42 and sliding blocks or lugs 47. The top edge 52 of the clamp stops a proper distance from the axle 42 (Fig. 5) so as not to interfere with the association of the inserted parts with those parts already in the body. This assembly is pushed, while held together in the clamp, upwardly into the cavity 18 in the toy body 11, being careful to thread the wing sections 43 of the axle 42 in the grooves 24 in fixed blocks 23 until (1) each lug 47 slides into a space 22 between the pair of blocks or ribs 20 and 21, and (2) the wing sections 43 of the axle 42 spring into the recesses 25 in blocks 23, thus seating themselves and locking themselves therein and also locking all the other parts temporarily held in the clamp 50 in operable position. The clamp is then removed, as the slots 51 permit, and the completed toy is ready for the market.

Rotation of friction wheel 40 by engagement of cam edge 45 of one cam 44 pushes one sliding lug 47 upwardly into engagement with one arm of the cross-arm 31 on rockable shaft 30 whereupon that shaft with the head 14 and tail 15 of the toy moves rotationally in one direction. Continued rotation of the friction wheel 40 permits the thus lifted lug 47 to fall back as the edge 45 of the cam passes it whereupon the rockable shaft with the toy's head and tail returns to normal. Further rotation of the friction wheel causes the edge 46 of the other cam 44 to engage the other lug 47, and this rocks the shaft 30 with its head and tail in the opposite direction—followed by the parts returning to normal. In this way, continued pulling of the toy causes the friction wheel 40 to rotate, which, if maintained, produces a rocking or wagging of the toy's head and tail.

By way of illustrating how parts or elements of this invention may be changed or modified without departing from the spirit of the invention, it may be stated that the bent axle member 42 may have substituted for it a coiled spring. The spring is compressed when the parts are in the clamp 50, but when the clamp is withdrawn, the coiled spring expands and locks itself in the apertures 25 which however, in this instance, can be straight or complementary to the ends of the spring.

I claim:

1. A toy having a two-part body adapted to be moved upon and over a supporting surface, which body has its two parts secured together along a vertical plane presenting a cavity extending into the body from the lower edge thereof; a horizontal shaft extending longitudinally through the body and through the cavity therein and substantially in said vertical plane; and means for rocking the shaft comprising a wheel disposed partially within the cavity and journaled transversely of the body and adapted to roll upon said surface, an axle bearing said wheel and having its ends supported each in one of the two parts of said body, cam means at each side of the wheel and unitary therewith, the cam means at

one side being staggered relative to those at the other side; the cam faces of said cam means being disposed within an area not exceeding the periphery of the wheel, and actuating means effective between the cam means and said shaft for rocking the shaft as the wheel is turned comprising a pair of transverse arms extending oppositely to each other from said shaft and adapted to be actuated by said respective cams, a vertically guided slidable and reciprocable motion transmitting pusher member disposed at each side of said wheel between each respective cam means and one of said arms cooperatively associated therewith, whereby said pusher members are alternately advanced by their respective associated cam means in effecting the rocking movement of said shaft when said wheel rotates as the toy is being moved over said surface.

2. A toy according to claim 1, in which the axle is of resiliently deflectable springy material, and in which guide means are provided on each of the two parts of the toy body within said cavity for guiding the ends of said axle when the axle together with the wheel and its cam means are inserted into the cavity, each of said guide means having a recess at the upper end thereof into which recess the respective ends of the axle are sprung.

3. A toy according to claim 1, in which the axle is of resiliently deflectable springy material, and in which guide means are provided on each of the two parts of the toy body within said cavity for guiding the ends of said axle when the axle together with the wheel and its cam means are inserted into the cavity, each of said guide means having a recess at the upper end thereof into which recess the respective ends of the axle are sprung, and in which said axle comprises a horizontal body portion carrying said wheel and said cam means and downwardly inclined end portions each substantially forming an obtuse angle with said body portion, each of said end portions engaging in one of said recesses.

4. A toy according to claim 1, in which the body represents that of a four-legged animal, in which the animal's head is fixed to the front end of said shaft, and the animal's tail is fixed to the rear end of said shaft.

ALBERT BEHRENS.
